US00D682902S

(12) **United States Design Patent**
Tanaka et al.

(10) **Patent No.:** US D682,902 S
(45) **Date of Patent:** ** May 21, 2013

(54) **REDUCTION GEAR**

(75) Inventors: **Satoshi Tanaka**, Tsu (JP); **Daisuke Matsui**, Tsu (JP); **Yusuke Kataoka**, Tsu (JP)

(73) Assignee: **Nabtesco Corporation**, Tokyo (JP)

(**) Term: **14 Years**

(21) Appl. No.: **29/407,310**

(22) Filed: **Nov. 28, 2011**

(30) **Foreign Application Priority Data**

Aug. 29, 2011 (JP) 2011-019458

(51) **LOC (9) Cl.** **15-99**

(52) **U.S. Cl.**

USPC **D15/149**

(58) **Field of Classification Search** D15/148, D15/149; 74/464; 395/395, 395.411, 464, 395/640; 427/249.19; 428/408; 475/83, 475/331, 344, 901

See application file for complete search history.

(57) **CLAIM**

The ornamental design for the reduction gear, as shown and described.

DESCRIPTION

FIG. 1 is a front perspective view of our new design for a reduction gear;

FIG. 2 is a rear perspective view of FIG. 1;

FIG. 3 is a left side elevation view of FIG. 1;

FIG. 4 is a right side elevation view of FIG. 1;

FIG. 5 is a front side elevation view of FIG. 1;

FIG. 6 is rear side elevation view of FIG. 1;

FIG. 7 is a top plan view of FIG. 1; and,

FIG. 8 is a bottom plan view of FIG. 1.

The broken lines in the drawings depict unclaimed environmental subject matter.
